UNITED STATES PATENT OFFICE.

WALLACE V. WOLFE, OF CORONA, NEW YORK, ASSIGNOR TO WESTERN ELECTRIC COMPANY, INCORPORATED, OF NEW YORK, N. Y., A CORPORATION OF NEW YORK.

MULTIPLEX SIGNALING SYSTEM.

Application filed November 29, 1922. Serial No. 603,907.

To all whom it may concern:

Be it known that I, WALLACE V. WOLFE, a citizen of the United States of America, residing at Corona, in the county of Queens and State of New York, have invented certain new and useful Improvements in Multiplex Signaling Systems, of which the following is a full, clear, concise, and exact description.

The present invention relates to signaling by means of carrier waves, and more particularly to provisions for the transmission of signals through a plurality of carrier wave channels constituting a multiplex system.

The invention relates particularly to the type of carrier transmission system in which the carrier wave is normally continuously transmitted, and in which the carrier waves of the various channels may be independently interrupted to transmit a signal over any particular channel. In the embodiment of the invention to be described, the normally continuously transmitted carrier waves are modified or modulated to transmit one kind of signal such as speech, for example, and are temporarily interrupted to transmit another kind of signal such as a call signal.

In systems of this character, sometimes termed closed circuit systems, the entire signaling circuit such as the line must be intact and the terminal apparatus must be in operative condition in order that the carrier waves may be continuously transmitted and received. An interruption to the transmission through the system due, for example, to a break in the line or in a common terminal circuit, or to adverse weather conditions in the case of a line system, or of a radio system, for example, may result in an interruption of each or a number of the carrier waves being transmitted, and such an interruption of all or a plurality of the received carrier waves may conveniently be taken as an indication of a failure of the system. This is particularly true since it is very improbable that all or a number of the carrier waves would be interrupted simultaneously in the normal operation of transmitting call signals over the various channels.

It is an object of the invention to provide for giving a signal in response to interruption of the carrier waves in a plurality of channels simultaneously.

This signal or alarm may be used to indi-

cate to an attendant a failure in the system, or a reduced or interrupted transmission of the carrier currents, as will be explained.

The general type of carrier current system to which the invention is particularly applicable, is shown and described in an article entitled "Carrier current telephony and telegraphy" by E. H. Colpitts and O. B. Blackwell, beginning in the April, 1921 Journal of the American Institute of Electrical Engineers, at page 420, Fig. 42.

The drawing to which the following description refers illustrates diagrammatically a system of the type shown in the Colpitts and Blackwell article with an embodiment of the invention incorporated therein.

Referring to the drawing, the line ML may be a multiplex carrier current line and the line LL may be one of a plurality of low frequency lines such as ordinary subscribers' loops arranged for two-way repeating to and from the carrier line. The main line, or carrier line, is provided with a balancing network MN and a conjugate repeating coil, or hybrid coil, H, having a transmitting loop TL and a receiving loop RL associated with the hybrid coil and conjugately related to each other. Each low frequency line is also provided with a balancing network LN and a hybrid coil as shown, having conjugate branches for respectively impressing currents on the line LL and deriving currents therefrom.

Each branch or repeating circuit for repeating signals from the low frequency line to the high frequency line comprises a modulator such as M_1 normally supplied with carrier current from a source such as S, and a band filter such as BF_4 for selectively transmitting to the transmission loop TL the range of frequencies set aside for the exclusive use of the particular channel. The repeating circuit for transmitting from the high frequency line to a low frequency line such as LL comprises a band filter such as BF_1 adapted to transmit selectively the range of frequencies used exclusively by this channel, a detector or demodulator DM_1 , and a low frequency or speech frequency filter LF for confining the currents transmitted to the line LL to the voice frequency range. Also associated with the output side of the demodulator DM_1 is a high frequency filter HF, selective of the carrier frequency, and a rectifier R_1 for supplying the rectified

carrier frequency current to a control relay 10. Each of the filters BF_1 , HF_1 , LF and BF_4 may be of the type described in the Colpitts and Blackwell paper referred to and more fully disclosed in the patent to G. A. Campbell No. 1,227,113, issued May 22, 1917. The modulator M_1 and the rectifier R_1 are preferably of the vacuum tube type such as are indicated in Fig. 42 of the Colpitts and Blackwell paper referred to. Also the carrier frequency source indicated at S is preferably of the vacuum tube type having a regenerative connection for causing the continuous production of oscillations, although this source may be of any other suitable type such as a machine generator.

The filter BF_2 and the demodulator DM_2 are assumed to comprise the receiving side of a second carrier channel leading to a second low frequency line which is not shown, but which may be entirely similar to the line LL . This channel employs a carrier current of a frequency different from that used in the channel previously described and the band filter BF_2 is designed in accordance with the principles set forth in the Campbell patent referred to, so as to have a selective transmission range for the currents of the frequency range used exclusively by this channel. Similarly the filter HF_2 is selective of the carrier wave transmitted over this particular channel. The circuit for transmitting from the second low frequency line (not shown) to the multiplex carrier line ML by way of the common transmission loop TL is indicated by the branch 11.

The band filter BF_3 , demodulator DM_3 , filter HF_3 and rectifier R_3 are in a similar manner associated with a third low frequency line which is not shown in the drawing, but which may be a duplicate of the line LL and the circuit for transmitting from this third assumed low frequency line to the transmission loop TL is indicated by the connecting terminals 12. Associated with the rectifier R_2 is a relay 13 and associated with the rectifier R_3 is a relay 14. The filters HF_1 , HF_2 and HF_3 may in each instance be a simple tuned circuit if desired. The relay 15, which is adapted to be actuated by the relays 10, 13 and 14 in common in the manner to be described below, is preferably marginal so that its armature is normally retracted and holds open the circuit of the alarm 16, except when a current exceeding a predetermined strength is flowing in the winding of the relay 15. The resistances 17, 18 and 19 may each be any desired type of current consuming indicating device such as a lamp or an electromagnetic signal. The purpose and function of the relays 20, 21 and 22 will appear from the description of operation of the system which will now be given.

The operation of the system in transmitting speech is substantially as described in the Colpitts and Blackwell paper referred to. The speech frequency currents received from the subscribers' station on the line LL are repeated into the circuit of modulator M_1 where they combine with the carrier wave from the source S in well known manner to produce a voice modulated high frequency wave. This wave is selectively transmitted by band filter BF_4 to the branch TL and to the multiplex line ML for transmission to a distant station. The manner in which the wave is received and again converted into speech at the distant station will be clear from considering a similarly modulated wave received at the station shown. Such a wave received over the uppermost channel in the drawing, for example, is selectively transmitted by the band filter BF_1 to the demodulator DM_1 , which operates in well known manner to reproduce currents of the speech frequency range. These currents pass selectively through the low pass filter LF from which they are impressed on the line LL .

The relay 21 bridged across the telephone line LL is made selective of ringing or signaling current adapted to be transmitted from the distant station on the low frequency line, but remains inert when currents of different character such as speech currents or talking currents traverse the line LL . This selectivity may be secured in a manner well known in the art such as by including the condenser as shown in the circuit of the relay, and by proportioning the inductance of the winding and also, if necessary, the mechanical construction of the armature. Except when a ringing or calling signal is received over the line LL , relay 21 allows its armature to close continuously the energizing circuit for the relay 22. Relay 22 by continuously attracting its armatures permits a supply of carrier current from the source S to the modulator M_1 and through the band filter BF_4 to the main line ML . In a similar manner it is assumed that the carrier current is normally continuously supplied through the branches 11 and 12 to the line ML under control of other low frequency lines not shown. Similarly also at a distant terminal of the multiplex line ML , the corresponding low frequency lines with which the lines LL and similar lines at the station shown are adapted to converse, are assumed to maintain normally the supply of corresponding carrier currents to the multiplex line ML , except when a call signal is to be transmitted. Accordingly at the station shown in the drawing there is normally being received continuously a sustained carrier wave in each of the carrier channels associated with the line ML .

The carrier current normally continuously

received over any channel such as the uppermost channel illustrated in the drawing is selectively passed through the band filter BF_1 and passes into the demodulator DM_1 5 where a partial rectification takes place. The high frequency component of the output current from the demodulator DM_1 is selectively passed through the filter circuit HF_1 and is rectified by the device R_1 so as to be capable of energizing the relay 10. Similarly the carrier current normally received continuously over each of the other channels maintains the respective relays 13 and 14 in energized condition.

15 When it is desired to transmit a ringing or calling signal from a low frequency line such as LL through the corresponding carrier channel and out over the cooperating low frequency at a distant station on the line ML , ringing current of the character to which relay 21 is selectively responsive is transmitted over the line LL . Relay 21 in response to this ringing current pulls up its armature, opening the circuit of relay 22 which releases its armatures. The supply of carrier current to the modulator M_1 from the source S is thus interrupted for the duration of the calling signal received from the line LL . The effect of this interruption of the distant station will be understood from considering the effect at the station shown of an interruption in the carrier current normally continuously received. Considering the uppermost channel of the drawing an interruption of the received carrier in this channel allows the relay 10 to deenergize, whereupon a circuit is closed for the relay 20 from grounded battery, winding of relay 20, armature and back contact of relay 10, and the armature and front contact of one or all of the remaining relays 13, 14, etc. on the assumption that the carrier waves normally being received by these several channels will not all be simultaneously interrupted in the normal operation of transmitting calling signals. A circuit in shunt of the relay 20 is also closed from grounded battery and indicating device 17, armature and back contact of relay 10 and to ground as previously traced. Relay 20 pulls up its armatures for the duration of the interruption in the received carrier current and bridges across the portion of the line LL extending to the right from the hybrid coil a source of ringing current 23 of suitable type. Relay 20 in energizing, severs the connection of the line LL to the hybrid coil and to the bridged relay 21, so that currents on the line LL can have no effect upon the carrier terminal apparatus. The ringing current sent out over the line LL from the source 23 may serve, in accordance with standard practice, to actuate a signal device at the distant station of the line LL .

In an entirely similar manner, calling or ringing signals may be simultaneously and selectively transmitted through each of the other carrier channels by momentary interruption of the respective carrier wave. In 70 case of the simultaneous interruption of all or a number of the carrier waves normally being received, all or a plurality of the relays 10, 13 and 14, etc., will be simultaneously deenergized. The marginal relay 75 15, it will be noted, is included in a circuit in shunt to ground of the circuit for energizing relay 20 and signal device 17. In the normal operation of the system in transmitting a ringing current over a single one of 80 the channels, or over a plurality of channels less than a predetermined number, relay 15 will draw insufficient current from a path including battery and relay 20, and battery and resistance 17 in parallel, (or a 85 plurality of such paths in parallel if more than one channel are simultaneously calling) armature and back contact of one or a corresponding plurality of relays 10, 13, etc., resistance 24, and winding of relay 15 to 90 ground in parallel with one or more resistances 24, and armature and front contact of the relays 13, 14, etc., that may still be in energized condition. However, if all of the relays 10, 13, 14, etc., are simultaneously deenergized, or if more than a predetermined number are deenergized simultaneously, the current through the corresponding plurality of relays in parallel, through the corresponding indicating devices 17 in parallel, and through the winding of relay 15, will be sufficient to energize 95 this relay and cause it to pull up its armature to actuate the alarm signal 16. For example, in a five channel system the resistances 17, 18, 19 and 24 and the impedance of the windings of the relays 20 of the various lines may be so proportioned with respect to the characteristics of relay 15 that if the carrier current on four of the channels is interrupted simultaneously the relay 15 will energize, whereas if three or less than three of the carrier waves are simultaneously interrupted, the relay 15 will receive insufficient current to energize. If three or less than three carrier waves are interrupted simultaneously, it follows that two or more than two of the relays 10, 13, 14, etc., will be left energized and the energizing circuit for any given relay 20 to ground 105 through the front contacts of the relays 10, 13, etc., will include two resistances 24 in parallel, as well as the relay 15, in which case the relays 20 receive sufficient current to operate. If four of the five channels have their carrier waves simultaneously interrupted, the resistances 17, 18, 19, 24 and the relay 15 may be such that none of the relays 20 in question can be operated on account of the single remaining resistance 24 110

115

120

125

130

in the single remaining ground circuit. As explained above, however, relay 15 will under these conditions operate. By suitable adjustment therefore, the system may be arranged so that no ringing signal will be sent out on any low frequency line LL in case a ringing signal is simultaneously received over a plurality of carrier channels greater than a predetermined number, while under these same conditions the alarm 16 will be actuated. If desired, however, the system may be adjusted so that ringing signals simultaneously received over the various channels will be repeated over the respective lines, except in the single instance when the carriers in all of the channels are simultaneously interrupted, this being also the only condition on which the alarm 16 is operated. The invention lends itself, therefore, to various adjustments corresponding to interruption of transmission on all of the channels, or to a condition of reduced transmission through the system due to the cessation of current on a part of the channels only. This latter adjustment may be convenient, for example, in cases where the alarm 16 is to be actuated to indicate a change in the transmitting conditions which is selective in character and effects only the channels employing waves of certain frequencies.

While the invention has been described as applied to a specific type of transmitting system, it is to be understood that the invention is not limited to the particular type of system disclosed, nor to systems in which the carrier waves are transmitted over a conductive circuit, but that it is equally applicable to other types of line transmission systems than that disclosed and also to radio systems.

What is claimed is:

1. In a signaling system a plurality of carrier wave transmission channels, means to transmit signals through the respective channels comprising means for withdrawing the respective carrier waves from transmission, and a signal device actuated only in response to the condition of withdrawal of the carrier wave existing simultaneously in a plurality of said channels.
2. In a multiplex carrier signaling system a plurality of carrier signaling channels, means for normally continuously transmitting the carrier waves through the respective carrier channels, means for independently transmitting a signal through each of said channels in response to the withdrawal from transmission of the normally transmitted carrier wave of the respective channel, a signaling device, and means for actuating said signaling device in response to the condition of withdrawal of the normally transmitted carrier wave in a plurality of said channels at the same time.

3. In a multiplex carrier signaling system a plurality of carrier channels, means for normally continuously transmitting the carrier waves through the respective carrier channels, means for independently transmitting a signal through each of said channels in response to the withdrawal from transmission of the normally transmitted carrier wave, a signaling device, and means dependent upon the condition of withdrawal of the carrier waves existing simultaneously in a plurality of channels in excess only of a predetermined number for controlling said signaling device.

4. In a multiplex carrier wave system a plurality of distinct carrier wave transmission channels superposed on the same medium, means for normally continuously transmitting the carrier wave through each of said channels, a relay for each of said channels normally energized in response to the carrier transmitted through the respective channel, a signaling element associated with each of said relays, a signaling device common to said relays and means responsive to the deenergization of each of said relays for actuating the corresponding signaling element and responsive only to the simultaneous deenergization of a plurality of said relays in excess of a predetermined number for controlling actuation of said signaling device.

5. In a multiplex carrier wave transmission system, a plurality of distinct carrier wave transmission channels, means for transmitting signals through said respective channels, an alarm signal and means controlled by carrier waves received over said channels and responsive to a failure in the transmission system resulting in the condition of withdrawal from transmission of all of said carrier waves at the same time for actuating said alarm signal.

6. In a multiplex carrier wave transmission system, means to transmit normally and continuously a plurality of carrier waves of respectively different frequency, a corresponding plurality of signals, means responsive to the withdrawal from transmission of a carrier wave for actuating the corresponding signal, an indicating device and means dependent upon the condition of withdrawal at the same time of a plurality of said carrier waves for actuating said indicating device.

7. In a multiplex carrier wave transmission system, means for normally and continuously transmitting a plurality of carrier waves of respectively different frequency, a corresponding plurality of signals, means responsive to the withdrawal from transmission of a carrier wave for actuating the corresponding signal, means responsive to the condition of withdrawal at the same time of a plurality of said carrier waves for pre-

venting the response of any of said signals, an indicating device, and means dependent upon the condition of withdrawal at the same time of a plurality of said carrier waves for actuating said signaling device.

8. In a multiplex carrier wave signaling system, means for normally continuously transmitting a plurality of carrier waves of 10 respectively different frequency, a plurality of receiving circuits for the respective carrier waves, interlocking circuits between said receiving circuits, a plurality of signals each having a circuit controlled in the 15 interlocking circuits of said receiving circuits, a marginal relay also controlled in said interlocking circuits, means responsive to the withdrawal from transmission of a carrier wave for actuating the corresponding 20 signal and means responsive to the con-

dition of withdrawal at the same time of a plurality of said carrier waves for shifting said interlocking circuits to prevent the actuation of any of said signals and to actuate said marginal relay and an indicating 25 device controlled by said marginal relay.

9. In a carrier wave signaling system, a plurality of carrier wave channels, signals corresponding to said channels and arranged to be controlled individually over the respective channels, a signal common to a plurality of said channels, and means controlled simultaneously over said plurality of channels for actuating said last-mentioned signal.

In witness whereof, I hereunto subscribe my name this 25th day of November A. D. 1922.

WALLACE V. WOLFE.
